UNITED STATES PATENT OFFICE

103,978

DESIGN FOR A HAIR DRIER

Marion W. Pitner, Chicago, Ill., assignor to The National Mineral Company, Chicago, Ill., a corporation of Illinois

Application July 20, 1936, Serial No. 63,945

Term of patent 14 years

To all whom it may concern:

Be it known that I, Marion W. Pitner, a citizen of the United States, residing at Chicago, in the county of Cook and State of Illinois, have invented a new, original, and ornamental Design for a Hair Drier, of which the following is a specification, reference being had to the accompanying drawing, forming part thereof.

Fig. 1 is a perspective view of a hair drier showing my new design;

Fig. 2 is an elevational view on a large scale of the pedestal element shown in Fig. 1 with a portion of the standard broken away.

The dominant feature of my design resides in the pedestal portion shown in full lines.

I claim:

The ornamental design for a hair drier as shown and described.

MARION W. PITNER.
